(57) **CLAIM**

The ornamental design for dog chew, as shown and
described.

DESCRIPTION

FIG. 1 is a left side perspective view of a design for dog
chew showing our new design, the undisclosed right side
being a mirror image;

FIG. 2 is a right side perspective view of a portion of the
design for dog chew shown for clarity of disclosure;

FIG. 3 is a top plan view thereof;

FIG. 4 is a rear elevational view thereof; and,

FIG. 5 is a bottom plan view thereof.
